UNITED STATES PATENT OFFICE

157,407

COFFEE-MAKING APPARATUS

Peter Pappas, New Haven, Conn.

Application June 17, 1948, Serial No. 147,029

Term of patent 14 years

(Cl. D44—26)

To all whom it may concern:

Be it known that I, Peter Pappas, a subject of the King of Greece, residing in New Haven, in the county of New Haven and State of Connecticut, have invented a new, original, and ornamental Design for Coffee-Making Apparatus, of which the following is a specification, reference being had to the accompanying drawing, forming part thereof, in which:

Fig. 1 is a front elevational view of a coffee-making apparatus embodying my new design;

Fig. 2 is a top plan view thereof; and

Fig. 3 is a side elevational view of the apparatus.

I claim:

The ornamental design for a coffee-making apparatus, substantially as shown.

PETER PAPPAS.
